(57) **CLAIM**

The ornamental design for a medical syringe as shown and described.

DESCRIPTION

The patent or application file contains at least one drawing/photograph executed in color. Copies of this patent or patent application publication with color drawing(s)/photograph(s) will be provided by the Office upon request and payment of the necessary fee.

1. Medical syringe

1.1 : Perspective

1.2 : Perspective

1.3 : Front

1.4 : Back

1.5 : Left

1.6 : Right

1.7 : Top

1.8 : Bottom

FIG. 1.1 is a perspective view of the medical syringe showing a new design; FIG. 1.2 is a bottom perspective view thereof; FIG. 1.3 is a front view thereof; FIG. 1.4 is a rear view thereof; FIG. 1.5 is a left side view thereof; FIG. 1.6 is a right side view thereof; FIG. 1.7 is a top view thereof; and FIG. 1.8 is a bottom view thereof.

The yellow portions of the medical syringe in FIG. 1.4 form no part of the claimed design.

1 Claim, 8 Drawing Sheets
(1 of 8 Drawing Sheet(s) Filed in Color)
